CLAIM

The ornamental design for a refrigerator door, as shown and described.

DESCRIPTION

FIG. 1 is a top perspective view of a refrigerator door showing our new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is a bottom perspective view thereof; and,

FIG. 9 is a top perspective view thereof, with additional unclaimed environment.

(Continued)

The broken lines in the figures depict environment and portions of the refrigerator door that form no part of the claimed design.
